UNITED STATES PATENT OFFICE.

WALTER L. ALBER, OF CHICAGO, ILLINOIS.

HOLLOW-TILE-PARTITION TIE PIECE.

Application filed August 28, 1926. Serial No. 132,077.

This invention relates to means for attaching the upright studs or posts of a door frame in a door opening of hollow tile partitions of buildings, and has for its 5 object:

To provide a structural formation of a plate metal tie piece in which are combined the features of aligning engagement between the adjoining edges of the hollow tile 10 sections of a partition, the anchoring of the tie piece against horizontal shift when in place and means of attachment to an upright stud or post of a door frame, all as will hereinafter more fully appear.

15 In the accompanying drawing:

Fig. 1, is a fragmentary side elevation, showing the tie piece in place between sections of hollow tile and in engagement with the stud or post of a door frame.

20 Fig. 2, is a horizontal section, on line 2—2 Fig. 1.

Fig. 3, is a perspective view of the narrow type of the tie piece.

25 Fig. 4, is a similar view of the wide type of the same.

Like reference numerals indicate like parts in the different views.

The preferred form of the tie piece is 30 shown in Figs. 1, 2 and 3, and is adapted to fit the adjacent side walls of a pair of hollow tile sections 1 and 2 at the door opening of a building partition, the scope of the invention however embraces a formation of the tie piece so that the same will span the 35 entire thickness of the hollow tile sections of the narrow type.

In both types of the tie piece, the same is 40 formed from an approximately rectangular blank of plate metal having one or more tongues or extensions 3 at one end and formed with a pair of slits midway its length, so that when bent in to a channel shape the structure will comprise outer and inner side webs 4 and 5 in parallel relation 45 fixedly connected together by a central transverse connecting web 6, with the end portions of said webs 4, 5, extending upwardly to provide pairs of outer and inner side flanges 7 and 8 in parallel relation to 50 provide a receiving channel for a wall por-

tion of a hollow tile section 1 as hereinafter more fully set forth.

In the preferred form of the invention, above referred to, the tie piece will have a single tongue or extension 3 extending from 55 the outer side web 4 aforesaid, while the other form of the tie piece, each side web 4 and 5 will be provided with similar tongues 3, as shown in Fig. 4.

A material part of the improvement consists in forming the webs 4 and 5 and side flanges 7 and 8 with inwardly projecting anchor prongs 9 adapted to engage in the usual surface grooves 10 formed in many hollow tile sections, or in specially formed 65 recesses in the plan surfaced tiles, and for the purpose of resisting longitudinal shift of the tie piece.

In the narrow type of the tie piece, the transverse connecting web 6 is integrally 70 formed with the side webs 4 and 5, while in the wide type of the tie piece, the said connecting web 6 will be formed as a separate part and secured by angular flanges and rivets to separately formed side webs 75 4 and 5, with a view to economy of manufacture, and as shown in Fig. 4.

In a practical application, the tie piece is positioned so that the transverse connecting web 6 rests upon the upper end of 80 a hollow tile section 2, with the depending webs 4 and 5, in contact with opposite faces of the tile section, while the pairs of upstanding side flanges 7 and 8 provide a channel for the reception of and engagement 85 with the lower end of a superimposed tile section 1 as shown in Fig. 1, and with the tongue or extension 3, in contact with a side of the door frame post or upright 11, with a fixed attachment thereto attained by nails 90 driven into said post through nail holes formed in said tongue or extension.

Having thus fully described my invention what I claim and desire to secure by Letters Patent is:

1. A tie piece of the type described, comprising in combination a pair of side webs having upstanding end portions, a connecting web arranged at the mid-height and mid-length of said side webs, and an exten- 100

sion at one end of a side plate for attachment to a door post, the side webs having inwardly projecting anchor prongs near their respective ends.

5. 2. A tie piece of the type described, comprising in combination a pair of side webs having upstanding end portions, a connecting web arranged at the mid-height and

mid-length of said side webs, and an extension at one end of a side plate for attachment to a door post, the side webs and their upstanding portions carrying upper and lower movable projecting anchor prongs.

Signed at Chicago, Illinois, this 26th day of August, 1926.

WALTER L. ALBER.
